J. E. CHRISTENSEN ET AL

CANDY BOX

Filed Oct. 6, 1923

Inventor:

John E. Christensen.
Harry P. McDerney
By Milo B. Stevens, Jr.

Attorneys.

UNITED STATES PATENT OFFICE.

JOHN E. CHRISTENSEN AND HARRY P. McNERNEY, OF CHICAGO, ILLINOIS.

DESIGN FOR A CANDY BOX.

Application filed October 6, 1923. Serial No. 7,413. Term of patent 14 years.

To all whom it may concern:

Be it known that we, JOHN E. CHRISTENSEN and HARRY P. McNERNEY, citizens of the United States, residing at Chicago, in the county of Cook and State of Illinois, have invented a new, original, and ornamental Design for a Candy Box, of which the following is a specification, reference being had to the accompanying drawing, in which the figure is a perspective view of a candy box embodying our design.

We claim:—

The ornamental design for a candy box, as shown.

In testimony whereof we affix our signatures.

JOHN E. CHRISTENSEN.
HARRY P. McNERNEY.
